H. O. HEM

FULCRUM SUPPORT

Filed April 5, 1920

Inventor

HAROLD O. HEM

By

George R. Frye.

Attorney

UNITED STATES PATENT OFFICE.

HALVOR O. HEM, OF TOLEDO, OHIO, ASSIGNOR TO TOLEDO SCALE COMPANY, OF TOLEDO, OHIO, A CORPORATION OF NEW JERSEY.

FULCRUM SUPPORT.

Application filed April 5, 1920. Serial No. 371,877.

To all whom it may concern:

Be it known that I, HALVOR O. HEM, a citizen of the United States, residing at Toledo, in the county of Lucas and State of Ohio, have invented certain new and useful Improvements in Fulcrum Supports, of which the following is a specification.

This invention relates to weighing scales and particularly to means for supporting or fulcruming levers. Weighing mechanisms often include one or more levers, the fulcrums of which are suspended by means of a link usually from a shelf. Such levers are commonly called shelf levers. The means employed for attaching the link to the shelf is usually merely a hook bolt or eye bolt. Owing to its tendency to twist when the nuts are turned up, it is very difficult to properly position such an eye bolt. The eye bolt is not susceptible of adjustment and for this reason, or because of bending of the material of the shelf to which it is secured or bending of the shank of the bolt itself, out of plumb conditions often creep into the system and result in errors that are difficult to detect or avoid. One of the objects of this invention is to provide a device for supporting a lever from a shelf which is so secured to the shelf as to eliminate danger of the shelf's bending.

Another object is to provide a supporting device which is itself incapable of appreciable distortion.

Another object is to provide a supporting bracket which may be accurately adjusted and positioned.

Still another object is to provide a device to support a shelf lever on knife edge pivots.

Other objects and advantages will be apparent from the following description, in which reference is had to the accompanying drawings illustrating a preferred embodiment of my invention and wherein similar reference numerals designate similar parts throughout the several views.

In the drawings:—

Figure 1 is a front elevation of a scale cabinet showing a shelf lever supported by the bracket of my invention;

Figure 2 is an enlarged front elevation of the shelf and bracket, parts being broken away; and

Figure 3 is a view taken from the right of Figure 2.

It is to be understood that the type of scale illustrated in Figure 1 is merely ex-

emplary and that my invention is equally adapted for use in scales of other types. In this figure a cabinet 1 is shown surrounded by a substantially watch-casing-shaped housing 2 which contains automatic load-offsetting mechanism (not shown) suitably connected to the indicating hand 3 which swings over a dial 4. A hook rod 5 depends from the mechanism within the casing 2 and is connected at its lower end by means of a stirrup 6 to a beam lever 7 fulcrumed upon a stand 8 which in turn is supported by a shelf 9 within the cabinet 1.

From the lever 7, to which its upper end is connected by means of a stirrup 10, an adjustable link 11 depends through an opening in the shelf 9, its lower end being connected by means of a stirrup 12 to one end of a shelf lever 13 which is connected through a stirrup 14 and steelyard 15 to the platform lever mechanism (not shown) of the scale. The other end of the shelf lever is supported, through the link 16 and stirrups 17 and 18, from the bracket 19 of my invention.

This bracket comprises a plate 20 of considerable area having a boss 21 on its lower side in which is set a knife-edge pivot 22 to project from each side thereof with its knife edges turned upwardly. In order to strengthen the structure and give it a finished appearance, gussets or braces 23 and 24 are formed between the sides of the plate 20 and the sides of the boss 21. Tapered elongated bolt openings 25 are provided at the ends of the plate 20, and surrounding each of said openings upon the upper face of the plate 20 is an annular boss 26. The shelf 9 is provided with bolt holes 27 so that in assembling the device the bracket 28 may be approximately positioned beneath the shelf and bolts 28 passed through the bolt holes 27 and the openings 25 and screwed into nuts 29, which are preferably of such size and shape that they are prevented from turning by the flanges or gussets 23 and 24.

It is apparent that the bracket may, because of the elongation of the openings 25, be moved forward and back until the connections are plumbed, and that when the bolts 28 are screwed into the nuts the bosses 26 are permanently clamped against the shelf at widely separated points, thereby reinforcing the shelf so that there is little

likelihood of its becoming bent in use. Also, since the knife-edge pivot of the bracket is located substantially midway of the bosses 26, the force exerted on this pivot by the 5 downward pull of the steelyard on the lever 13 will be divided between the bosses and thus distributed over a wide area.

The knife edge pivotal connection between the bracket and stirrup 18 not only relieves 10 the bracket of some of the strains that would otherwise be set up, but also reduces friction at this point and thereby increases the accuracy of the weighing mechanism as a whole.

15 While it will be apparent that the illustrated embodiment of my invention herein disclosed is well calculated to adequately fulfill the objects primarily stated, it is to be understood that the invention is susceptible to variation, modification and change 20 within the spirit and scope of the subjoined claims.

Having described my invention, I claim:

1. In a device of the class described, in 25 combination, a bracket, a knife edge pivot secured to said bracket, a link depending from said pivot, and a shelf lever, said shelf lever having its fulcrum supported by said link.

30 2. In a device of the class described, in combination, a bracket, a support therefor, means for adjustably mounting said bracket upon said support, a knife edge pivot secured to said bracket, a link depending 35 from said knife edge pivot, and a shelf lever, the fulcrum of said shelf lever being supported by said link.

3. In a device of the class described, in 40 combination, a weighing scale frame, including a shelf, a lever supporting bracket mounted on said shelf, said bracket having a knife edge pivot secured thereto, a link depending from said pivot, and a shelf lever, the fulcrum of said shelf lever being 45 supported by said link.

4. In a device of the class described, a

lever supporting bracket comprising, in combination, a plate having a pair of elongated openings, a boss formed upon the lower face of said plate, and gussets between the sides of said beam and the sides of said plate forming nut-engaging flanges at the sides of said openings. 50

5. In a device of the class described, a lever supporting bracket comprising, in combination, a plate having a pair of elongated openings, a boss formed upon the lower face of said plate, gussets between the sides of said boss and the sides of said plate forming nut-engaging flanges at the sides of said openings, and annular raised portions on the upper face of said plate surrounding 55 said openings.

6. In a device of the class described, a shelf lever supporting bracket comprising 60 a plate having a plurality of bosses adapted to engage the shelf at widely separated locations, and a pivot supported from said plate intermediate said bosses.

7. In a device of the class described, a shelf lever supporting bracket comprising 65 a plate having a plurality of bosses adapted to engage the shelf at widely separated locations, a depending member on said plate arranged intermediate the bosses, and a pivot 70 mounted in said member.

8. In a device of the class described, a lever supporting bracket comprising, in combination, a plate having a pair of elongated openings, a boss formed upon the lower face of said plate, gussets between the sides of said boss and the sides of said plate forming nut engaging flanges at the sides 75 of said openings, annular raised portions on the upper face of said plate surrounding 80 said openings, and knife edge pivots projecting from the sides of said boss.
